UNITED STATES PATENT OFFICE.

LOUIS ZWEIG, OF BROOKLYN, NEW YORK, ASSIGNOR TO SUN RISE LAMP MFG. CO., INC., A CORPORATION OF NEW YORK.

DESIGN FOR A TABLE LAMP OR ANALOGOUS ARTICLE.

Application filed July 12, 1927. Serial No. 22,731. Term of patent 3½ years.

To all whom it may concern:

Be it known that I, LOUIS ZWEIG, a citizen of the Republic of Austria, and a resident of Brooklyn, county of Kings, and State of New York, have invented a new, original, and ornamental Design for a Table Lamp or Analogous Article, of which the following is a specification, reference being had to the accompanying drawing, forming a part thereof.

In these drawings:

Figure 1 is a side elevational view of the table lamp or analogous article;

Figure 2 is a top plan view; and

Figure 3 is an elevational view taken in the direction of the arrow A of Figure 2.

The dominant features of the design consist in a boat B surmounted by a superstructure C including a grille D forming window openings which overlie a translucent sheet E; and a plurality of spreading lamp supporting arms F rising from the superstructure.

I claim:

The ornamental design for a table lamp or analogous article substantially as shown and described.

LOUIS ZWEIG.
